UNITED STATES PATENT OFFICE.

SIGMUND L. LEDERER, OF PROVIDENCE, RHODE ISLAND.

BRACELET.

No. 879,881.

Specification of Letters Patent.

Patented Feb. 25, 1908.

Application filed April 17, 1907. Serial No. 388,754.

To all whom it may concern:

Be it known that I, SIGMUND L. LEDERER, a citizen of the United States, residing at Providence, in the county of Providence and State of Rhode Island, have invented certain new and useful Improvements in Bracelets, of which the following is a specification, reference being had therein to the accompanying drawing.

10 My invention relates to concealed joint bracelets, or such as comprise two hollow hinged wings; and has for its object an improved combined guard and fastening means which shall be strong, durable, inexpensive 15 and applicable to both solid and plated bracelets.

To these ends essentially my invention consists of the novel construction and combination of parts hereinafter set forth, and 20 illustrated in the accompanying drawings, wherein,

Figure 1 is a top plan elevation of a bracelet embodying my invention. Fig. 2, a longitudinal section of the adjacent ends of the 25 same in engaged position. Fig. 3, a like section of the same in disengaged position. Fig. 4, an end elevation of one of the wings. Fig. 5, a section on line $x-x$ of Fig. 2. Fig. 6, a section on line $y-y$ of Fig. 3. Fig. 7, a plan elevation of the spring catch, and Fig. 8, a 30 central longitudinal section of the adjacent bracelet parts, showing in side elevation a modified form of my guard and catch.

Like reference characters indicate like 35 parts throughout the views.

My bracelet comprises the tubular wings, A and B, hinged at C, in any convenient manner. Soldered or otherwise fixed within the 40 end of wing B, and projecting therefrom, is a cap, b, whose top wall, b' , is provided with an oblong opening, b^2 . The adjacent end of the wing, A, has an opening, a, in its upper portion near its end. Within the wing, A, is a flat metallic spring loop, D, comprising the 45 upper and lower arms d and d' respectively, both arms being preferably transversely curved to conform to the curve of the wing. The spring character of the loop, D, forces the arms into contact with the top and bottom 50 tom of the wing wall, A. Near the forward end of the spring arm, d , is a projection, d^2 , which projects through the opening, a, pro-

vided with a nail channel, d^3 . The forward end of the arm, d , is downwardly inclined as at d^4 , and is provided with a slot, d^5 , in its inclined portion in front of the projection, d^2 . The lower spring arm, d' , is provided in its end with a longitudinal slot, d^6 , in which is fixed by soft solder, d^7 , the end of the guard or guide rod, E. The latter is provided near 60 its soldered end with a transverse bend, e; and the free end of the rod is bent to form a hook, e' . The hook is of greater width or diameter than the length of the opening, b^2 , of the cap, b, through which the rod passes. 65

In operation the end of the arm, d , acts as a spring latch. When closed, the end of the wing, A, rests over the projecting end of the cap, b, and abuts against the wing, B; while the top wall, b' , of the cap registers in the 70 slot, d^5 , of the arm, d ; as shown in Fig. 2. The parts are unlatched by pressing down upon the projection, d^2 . The unlatched ends may then be distended until the top wall of the cap, b, contacts with the end of the hook, e' . 75

If desired, the rod, E, may be fixed to the end of arm, d , instead of the arm, d^2 , as shown in Fig. 8.

The described connection of the arm and loop makes it possible to utilize the structure 80 for plated goods as it avoids the annealing effect of hard soldering. It will be observed that by the above construction the guard and spring parts are engaged with the bracelet wings without the use of solder. 85

What I claim is,

1. In a bracelet two hollow wings hinged together, a cap fixed in one wing and provided with an opening, a spring loop mounted in the other wing, a latch upon one end of the 90 loop adapted to engage the cap, a guide rod upon the other end of the loop traversing the opening, and a hook upon the end of the guide rod within the first-mentioned wing.

2. In a bracelet two hollow wings hinged 95 together, a spring loop in one member, a latch upon the loop, a rod upon the loop, a hook upon the rod, and means in the other wing adapted to engage the latch and the hook.

3. In a bracelet two hollow wings hinged 100 together, a cap fixed in one wing and provided with an opening in its top wall, a two arm spring loop mounted in the other wing, a recess in one arm of the loop adapted to re-

ceive the margin of the cap wall, a slot in the other arm of the loop, a guide rod fixed in said slot, extending through the opening, and a hook upon the guide rod within the wing first mentioned.

4. In a bracelet two hollow wings hinged together, a spring loop provided with a slot within one member, a latch upon the loop, a rod fixed within the slot in the loop, a hook

upon the rod, and means in the other wing to adapt to engage the latch and hook.

In testimony whereof I have affixed my signature in presence of two witnesses.

SIGMUND L. LEDERER.

Witnesses:

HORATIO E. BELLOW,

WALTER EDWARD GOODWIN.
